CONVERTIBLE GARMENT-FORM.

1,268,560.

Specification of Letters Patent.

Patented June 4, 1918.

Application filed January 5, 1918. Serial No. 210,543.

To all whom it may concern:

Be it known that I, STELLA S. FLEISHEL, a citizen of the United States, residing in the borough of Manhattan, city, county, and State of New York, have invented a new and useful Improvement in Convertible Garment-Forms, of which the following is a description.

This invention relates to wearing apparel for females and, particularly, has reference to a garment-form convertible into garments of the *negligée* type.

Among the objects of my invention may be noted the following: to provide a garment-form so constructed that it may be converted, when draped upon the wearer, into many different styles and designs of *negligée* garments; to provide a garment-form which may be converted into a plurality of *negligée* garments of the *kimono* type, by draping upon the figure in many different ways and which, by the addition of merely a girdle, belt, or waistband, may be made quite dressy; to provide a garment-form which is reversible upon the body of the wearer whereby to change the effects and drapery of the garment upon the person; to provide a garment-form which, when made of predetermined size, will fit the figures of different persons equally well, or will correspond to different sizes of garments; and to provide a simple, economical garment-form to which ornamental devices of various kinds can be applied for giving functional and esthetic effects and making the drapery upon the figure more or less dressy.

With the above objects in view and others which will be detailed during the course of this description, my invention consists in the parts, features, elements and combinations thereof hereinafter described and claimed.

In order that my invention may be clearly understood, I have provided drawings wherein:

Figure 1 is an inside plan view of a garment-form embodying my invention;

Fig. 2 is a section on line 2—2, Fig. 1;

Fig. 3 is a perspective view, on a reduced scale, showing how the body portion is folded over;

Fig. 4 is a front elevation of a garment

produced from the garment-form of Fig. 1; and

Fig. 5 is a plan view, broken to curtail the figure, showing a form of girdle, belt or waistband which may be used to add to the effects capable of being produced by draping the garment-form.

The garment-form will be described with reference to the parts of the body of the wearer so as to give a better idea of my invention.

Referring to the drawings, the numeral 1 indicates a long length of fabric one end of which is, preferably, deeply hemmed, as at 2, in order to provide a substantial finish to the end of the garment and enable the girdle effect of Fig. 4 to be produced. The length of this piece will depend upon the height of the wearer and the particular effects desired. The sides of this piece are also finished, as by hemming 3, and the bottom is finished, as by a substantial hem 4. The strip of fabric 1 is provided, at a selected, suitable point with a slit, or an opening 5, of any desired form, according to the effects desired. The opening 5 extends longitudinally of the fabric-strip and its edges are finished, as by hemming or binding 6, as may be desired. Preferably, the opening 5 is located centrally of the width of the fabric-strip 1 for most of the effects desired, although, for some effects, the opening may be located more or less to one side, as well as more or less distantly removed from the hemmed edge 2. Extending from a predetermined point in the length of the fabric-strip 1 to the bottom thereof, a shorter fabric-strip 7 is applied, the latter being connected to the longer fabric-strip at its opposite edges by inturned seams 8. The upper end of the fabric-strip 7 is provided with a hem 9, forming a pocket for a draw-string 10, long enough to tie around the waist of the wearer. The bottom of the fabric-strip 7 is hemmed, as at 11. Ornamental devices 12, such as tassels, brocade-forms, pendants, fringe, and other ornamental media may be applied to the ends of the single thick fabric, to the opposite sides and ends of the neck-opening 100 and to other portions of the form, as may be desired. In Fig. 1, I have shown a dotted

line 13 extending across the fabric-strip 1, substantially midway of the slit 5, to indicate the position of the shoulders of the wearer when the garment-form is draped 5 upon the latter.

The particular material used is not of the essence of my invention; but, I have obtained beautiful effects with silks,—figured and plain,—velvet, and combinations of 10 various materials.

Added effects are obtained by the use of a girdle or belt 14, Fig. 5, which may be made of corresponding or contrasting material, and provided with suitable fastening means 15 15 at opposite ends, and with ornamental devices 16. The fabric-strips 1 and 7 may be lined, if desired.

The garment-form thus produced will be seen to have, or may be conveniently de- 20 scribed to have, the following physical features corresponding to a negligée garment or lady's dress:

The upper portion of the single fabric-strip 1, according to the manner in which it 25 is placed upon the body of the wearer, becomes either the upper front or back body part of the garment. The head of the wearer is extended through the slit 5, so that the said upper body portion naturally 30 drapes about the shoulders of the wearer and the entire garment-form is primarily supported by the latter, the dotted line indicating the position of the shoulders of the wearer, when the garment-form is thus ad- 35 justed upon the body of the wearer. As shown in Fig. 4, the ornamental device 12 becomes a pendant at the front of the garment, while the two corner ornamental devices 12, shown in Fig. 1, are tied or inter-looped at the back of the wearer.

The double thick fabric portion of the garment-form becomes the skirt of the draped garment, and the shorter length 7 thereof becomes either the back or front portion 45 of said skirt, according to the manner in which the garment-form is adjusted upon the body of the wearer. Regardless of the manner in which the garment is draped upon the body of the wearer, the draw-string 50 10 becomes a waistband or medium by which the double thick portion of the garment-form is tied about the waist of the wearer, the said garment-form being gathered upon the draw-string 10 in order to create folds 55 of greater or less proportions around at least half of the body of the wearer, either the front half or the back half, accordingly as the garment-form is placed upon the body of the wearer.

60 Fig. 3 is intended to be suggestive of the manner in which the upper single fabric strip is thrown over the shoulders after extending the head of the wearer through the slit 5. The wearer steps into the skirt or

lower portion of the garment-form, drawing the same up about the waist, and then ties the ends of the draw-string 10 properly about the waist. Then the upper portion of the garment is thrown over the shoulders of the wearer, as above suggested and as shown 70 in Fig. 4, the head projecting through the slit 5.

The single thick portion 1, falling in front of the wearer, may be allowed to drape loosely over the body, or it may be turned outwardly, so as to make a deep girdle 75 about the waist of the wearer of the deeply hemmed portion 2, as shown in Fig. 4. When this is done, the ornamental devices 12 are interlooped at the back of the wearer, 80 as heretofore suggested. Any number of different effects can be secured, according to the way the garment-form is draped upon the body, and, if it is desired to have a very ornamental girdle or waist-band, the one 85 shown in Fig. 5 will be employed by drawing the same more or less tightly about the waist of the wearer, while the single thick portion of the garment hangs loosely from the shoulders, the hemmed portion 2 extending 90 below the girdle 14, and the adjustment of the latter resulting in giving to the garment-form the effect of loose, flowing, kimono sleeves. It will be understood that, if the shorter length of fabric 7 is draped 95 at the front of the wearer, the entire length of single thick fabric 1, at the back, from the dotted line 13, will extend loosely from the shoulders of the wearer downwardly to the heels, and assume the general outline of 100 the figure, while the remainder of the single thick fabric will become the front of the garment. The girdle 14, or the hemmed portion 2, for different effects, may be drawn about the waist to gather the said single 105 thick portions in long, graceful folds from shoulders to waist at the front, or from shoulders to feet at the back. The foregoing will be more or less true if the shorter length 7 is adjusted upon the body of the wearer to 110 be the back part of the garment; that is to say, the single thick fabric will then become the front of the garment and will hang in long, loose folds from the shoulders to the feet of the wearer modified in effect, accord- 115 ingly as the hemmed portion 2 or the girdle 14 is fastened about the waist of the wearer. The single thickness at the back, in two parts, will give the back of the garment different effects.

120 In the foregoing I have suggested only a few ways in which the garment-form may be adjusted and draped upon the body of the wearer; but, it will be readily understood by those skilled in the art that many 125 modifications and different drapery effects can be obtained according to the manipulation and adjustment of the different parts

of the garment-form and girdle 14. Moreover, different effects are produced, due to the ornamental media 12, accordingly as the shorter portion of the single thick fabric 1, 5 from the dotted line 13, is allowed to drop loosely or is gathered about the body as shown in Fig. 4; that is to say, the media 12 are selected with reference to their ornamental characteristics and weight, and when the 10 shorter portion of single thick fabric 1 is allowed to drop loosely from the shoulders, either in rear or front of the figure, the weight of said media, at the corners of the single thick material, will cause the latter to 15 assume long, graceful folds from the shoulders downwardly. When, however, the hem 2 is gathered about the body, as in Fig. 4, and the media 12 are interlooped, as explained, their weight will hold the hemmed 20 portion snugly in place and maintain the gathers or folds produced by this mode of drapery. The media 12, at one end of slit 5, has the function of holding the shorter portion of the single thick fabric 1 in place 25 as desired; that is to say, the tendency of the longer portion of the single thick fabric is to drag upon the shorter portion and cause it to draw upwardly toward the chin or back of the head accordingly as said shorter portion 30 is at the front or back of the wearer. In other words, the ornamental weight counterbalances or overcomes the greater weight of the longer portion of fabric strip 1, causing the garment to hold its place 35 properly on the figure and give comfort to the wearer. The media 12, therefore, are primarily selected with reference to their weight; but, should the same be selected because of purely ornamental characteristics, 40 a weight would be added, as at 12^a to produce the functions desired, said weight being covered by a piece of the material of which the garment-form is made, or with contrasting material to carry out the ornamental 45 effects.

From the foregoing it will also be understood that the garment-form can be made of a predetermined size so as to answer for persons of materially different sizes and 50 figures, since the form of the person gives shape to the garment-form and the latter is not intended to have a close fit. In other words, a single garment-form will answer for several persons requiring garments 55 ranging in size from 24 to 32 or from 34 to 42. The garment-form, therefore, is not only a medium for producing several different styles or forms of garments, but for producing said garments in the equivalent 60 of several different sizes.

Having thus described my invention, what I claim and desire to secure by Letters Patent is:

1. A garment-form consisting of a single

ply, upper, rectangular body portion and a 65 permanently tubular, lower skirt portion open at both ends, the single ply portion being provided with a substantially central, longitudinally extending slit through which to extend the head of the wearer so that said 70 single ply portion may drape over the shoulders of the wearer and take the form of a garment.

2. A garment-form comprising a single 75 ply, oblong body portion having an elongated slit for the head of the wearer, and a permanently tubular skirt portion open at both ends, and means located at the junction of the two portions for gathering the garment-form about the waist of the wearer, 80 whereby when the head of the wearer is extended through the slit in the body portion, the latter may take the form of a garment, and the skirt portion, through its gathering means, may assume the form of 85 the skirt of the garment.

3. A garment-form composed of an oblong strip of material of sufficient length to form the back of the skirt and entire body portion of a garment; and a second strip of 90 material, less than half the length of the first-named strip, permanently secured along its sides to the sides of the first-named strip, so as to form a tube open at both ends and complete the skirt portion of the garment; in combination with means for gathering the two strips about the waist of the wearer; and the first-named strip having a 95 slit therein through which the head of the wearer may be extended so as to cause the 100 said body portion to drape loosely over the shoulders of the wearer.

4. A garment-form, convertible into a plurality of negligée garments, composed of a strip of fabric oblong in form, having another strip permanently secured thereto along two of its sides and substantially half its length so as to form a tubular portion open at both ends, said form having means substantially at the point of termination of 110 the shorter strip for gathering the form about the waist of the wearer.

5. A garment-form rectangular in outline and composed of single ply fabric at one end and double ply, tubular fabric at the 115 other end, said form being entirely open at both ends of its double ply portion, the single ply fabric having a slit therein extending longitudinally thereof and remote from all its edges for the admission of the head 120 of the wearer, in combination with means for gathering the garment-form about the waist of the wearer.

6. A garment-form comprising a single 125 ply portion and a double ply, tubular portion open at both ends, the single ply portion having applied to different parts thereof weights or media for causing the said

single ply portion to properly drape upon the form of the wearer and take the form of a garment.

7. A garment-form comprising a single 5 ply portion and a double ply, tubular portion open at both ends, the latter constituting the skirt of the garment when draped upon the body of the wearer, the single ply portion being divided into a back and front

member by a slit for the head of the wearer, 10 one of said portions being of greater dimensions than the other of said portions, and means applied to different parts of one of the portions to cause the same to hang properly on the wearer and give the single 15 thick portion the form of a garment.

STELLA S. FLEISHEL.
